UNITED STATES PATENT OFFICE.

WAITMAN D. CORDER, OF PHILIPPI, WEST VIRGINIA.

SUSPENDERS.

1,351,553.

Specification of Letters Patent. Patented Aug. 31, 1920.

Application filed February 18, 1920. Serial No. 359,641.

To all whom it may concern:

Be it known that I, WAITMAN D. CORDER, a citizen of the United States of America, and resident of Philippi, county of Barbour, 5 and State of West Virginia, have invented certain new and useful Improvements in Suspenders, of which the following is a specification.

This invention relates broadly to suspenders, and more particularly to an elastic end 10 for suspenders.

The primary object of the invention is to provide a simple and inexpensive end construction for suspenders which affords 15 the requisite amount of elasticity and which, consequently, permits of dispensing with the employment of the usual elastic webbing in the body of the suspender.

A further object is to provide a resilient 20 tension device for suspenders having a construction affording remarkable efficiency and exceptional durability.

In describing the invention in detail, reference is herein had to the accompanying 25 drawings, in which—

Figure 1 is a partial sectional view of a suspender end embodying the invention;

Fig. 2 is an edge view of the same; and—

Fig. 3 is a partial longitudinal section.

Referring to said drawings, 1 indicates 30 a suspender strap formed of inelastic webbing, and 2 designates a pocket formed in an end of said strap by doubling the latter back upon itself and attaching the doubled-over portion 3 to the portion 4 located rearward thereof, as by rows of stitching extending across the upper end of the portion 3 and along the opposite lateral edges of the portions 3 and 4.

Suspended centrally within the pocket 2 40 is a loop 5 of tape or other suitable flexible material having its ends suitably attached at the upper end of the pocket, as by means of the same stitching which secures the upper end of the webbing portion 2 in place.

A transversely disposed bar 6 has a supporting bail 7 of inverted-U shape fixed thereto, and the tape of the loop 5 is passed through said bail so that said bar is supported by 50 said loop, the latter having such length that said bar is supported at the extreme lower end of the pocket. Said bar has eyes 8 formed in the opposite ends thereof in register with eyes 9 provided in the webbing at 55 the lower end of the pocket.

Extending upward into the pocket

through the opposite registering eyes 9 and 8 are the two similar end members of a doubled or looped cord 10 which has its loop end 10^a located outside said pocket, 60 Said end members of the cord extend upward and inward and meet between the members of the loop 5 at a point adjacent to the upper end of the pocket. The meeting ends are secured together by means of 65 a clamp 11. Disposed in encircling relation to each of said end members and interposed between said clamp 11 and the bar 6 is a coil compression spring 12.

As is obvious, the bar 6 serves as a 70 spreader whereby the members of the looped cord 10 are maintained separated to the extent that the springs 12 carried thereby do not interfere one with the other, and also whereby said members are maintained in 75 positions in which they may freely pass through the eyes 9.

From the foregoing it will be understood that a downward pull on the looped cord 10, or an upward pull on the webbing strap 1, 80 results in placing the two springs 12 under compression, the coupled or clamped ends of the loop members being actuated to move downward toward the bar 6 against the tension of said springs. 85

What is claimed is—

1. A suspender comprising an inelastic webbing shaped to form a pocket which has eyes formed in its lower end, a member depending within said pocket, a bar suspended 90 upon said member at the lower end of said pocket, said bar having eyes in its opposite ends in register with the eyes in said pocket, a looped cord with its loop-end located outside said pocket and having its opposite 95 end portions extending through the registering eyes of said pocket and said bar into the interior of said pocket, means connecting the upper ends of said end portions, and coil compression springs encircling said end portions and interposed between said connecting means and said bar. 100

2. A suspender comprising an inelastic webbing shaped to form a pocket at an end thereof and having eyes formed therein at the lower end of said pocket, a bar disposed transversely in said pocket adjacent to the lower end thereof, means suspending said bar, said bar having eyes in register with those in the pocket, a looped cord with its loop-end located outside said pocket and having its opposite end portions extending 110

upward through said registering eyes and thence convergently inclined into meeting relation, means connecting said meeting ends, and coil compression springs carried by said end portions between said connecting means and said bar.

3. A suspender comprising an inelastic webbing shaped to form a pocket at an end thereof and having eyes formed therein at 10 the lower end of said pocket, a bar disposed transversely in said pocket adjacent to the lower end thereof, means suspending said bar, said bar having eyes in register with those in the pocket, a looped cord with its

loop-end located outside said pocket and 15 having its opposite end portions extending upward through said registering eyes and thence convergently inclined into meeting relation, a clamp securing the meeting ends together, and coil compression springs carried by said end portions between said clamp and said bar. 20

In testimony whereof, I affix my signature in presence of two subscribing witnesses.

WAITMAN D. CORDER
